UNITED STATES PATENT OFFICE.

DAVID HIRSCH, OF SAN FRANCISCO, CALIFORNIA.

ARTIFICIAL HAND.

1,362,793.

Specification of Letters-Patent. Patented Dec. 21, 1920.

Application filed July 13, 1918. Serial No. 245,777.

To all whom it may concern:

Be it known that I, DAVID HIRSCH, a citizen of the United States, and a resident of the city and county of San Francisco, State of California, have invented a new and useful Improvement in Artificial Hands, of which the following is a specification.

My invention relates to improvements in artificial hands wherein separable matching hooks operate in conjunction with an improved and novel construction to rotate said hooks when the elbow is bent and certain back or arm muscles are tensioned or flexed; and the objects of my invention 15 are—

First, to provide a new and improved construction for artificial hands;

Second, to provide an improved construction of the class described whereby a greater 20 adjustability of the hand relatively to the arm of the operator may be obtained;

Third, to provide an improved construction for artificial hands and the like which may be assembled easily and cheaply to 25 provide a hand having a maximum utility and strength;

Fourth, to provide an improved construction for quickly and easily attaching and detaching the hand from the arm or stump 30 socket;

Fifth, to provide an improved construction wherein the hand detaching and rotating means may be embodied within one piece; and

Sixth, to provide an improved construction for artificial hands and the like wherein a greater leverage may be applied to the 35 rotating and hook separating means thereby permitting the provision of greater reacting mechanisms to impart greater strength to the manipulations of said hand.

I accomplish these several objects by means of the improved construction disclosed in the drawings forming a part of 45 the present specification wherein like characters of reference are used to designate similar parts throughout the said specification and drawings, and in which—

Figure 1 is a general view of the arm as 50 applied to an operator;

Fig. 2 is an enlarged view partly in vertical section of the matching hooks and operating mechanism therefor in an inverted position;

Fig. 3 is a side elevation of the reverse

side of the mechanism with the hooks detached therefrom;

Fig. 4 is a bottom plan view of Fig. 2;

Fig. 5 is a plan view of Fig. 2 with the hooks removed; and

Fig. 6 is a bottom plan or end view of the hooks removed from the operating mechanism therefor.

Referring to the drawings the numeral 1 is used to designate a socket to receive the 65 stump of the amputated arm as disclosed in Fig. 1 of the drawings. To the lower end of the stump is secured a metallic cup 2 by means of metallic side pieces 3, said cup 2 being provided with a slot 4 and a reduced tubular portion 6 within which is 70 rotatably mounted an internally threaded sleeve 7 having an annular flange 8 on the inner end thereof provided with a lateral beveled groove 9.

A sleeve 11, provided with a radially 75 grooved flange 12 on the outer end thereof, is rigidly screwed within the internally threaded sleeve 7 so as to provide substantially a single member comprising the 80 sleeves 7 and 11, the purpose of which will hereinafter be more fully set forth.

As the flanges 8 and 12 are of greater diameter than the ends of the reduced portion 6 it is evident that both sleeves will be held 85 against longitudinal movement while rotatably mounted within said reduced portion.

The grooves of the radially grooved flange 12 are provided to receive a pin 14 extending laterally from a cylindrical shank or stud 16 of a hook 17 having pivotally mounted thereon a hook 18 matching with said hook 17 at the outer end thereof.

The hooks 17 and 18 are normally held closed by means of a suitable spring 20. 95 The movable hook 18 is provided with an arcuate extension 19 adapted to serve as a thumb to the operator and also as a lever by means of which the hook 18 may be separated from the hook 17. The arcuate extension 19 is provided with an eyelet 21 to which a cord may be secured to operate said hook 18 in a manner hereinafter more fully described.

Slidably mounted within the beveled groove 105 9 of the annular flange 8 is a latch 22 having an aperture 23 therein actuated to move under a beveled head 24 of a screw 26, screwed into the inner end of the shank or stud 16 of the hook 18, by means of a spring 110

27. A pin 28 in the latch 22 limits the movement of the said latch 22 when the beveled head 24 of the screw 26 is disengaged therefrom.

5 By moving the latch 22 inwardly against the tension of the spring 27 the aperture 23 will register with the beveled head 24 of the screw 26 and thereby disengage said head 24. The hooks 17 and 18 may be then 10 partially withdrawn from the sleeves 7 and 11 and partially rotated and again moved into said sleeves to cause the pin 14 to engage a different groove in the radially grooved head or flange of the sleeve 11 there- 15 by providing a means whereby the position of the hooks 17 and 18 may be adjusted relatively to the sleeves.

The outer end of the latch 22 extends through the slot 4 in the metallic cup 2 and 20 has a lateral extension 29 provided with a pin 31 to which an operating cord 32 is attached, said cord 32 then passing over a pulley or roller 33 rotatably mounted upon one of the metallic side pieces 3 and under a 25 guard 34 having inclined extensions 36 to retain the cord 32 when slack.

After leaving the pulley or roller 33 the cord 32 passes along the back of the socket 1 and is attached to a leather strip 37 connecting the socket 1 and upper corset 38 arranged to be laced or otherwise secured to the upper portion of the arm of said operator.

The socket 1 is hingedly connected to the 35 corset 38 by means of metallic side pieces 39 and 40 secured to the said corset 38 and the socket 1 respectively, as at 41.

A suitable harness 42 secures or holds the corset 38 in position upon the body of the 40 operator.

A cord 43 is attached to the eyelet 21 of the arcuate thumb piece or extension 19 of the hook 18 and is separated into two sections 44 which pass on either side of the 45 socket 1 and through suitable guides or eyelets on the side pieces 39 of the corset 38 and after traversing the length of said corset 38 are again joined into a single strand or cord 46 which is attached to the rear of 50 the harness 42 or in some cases passes to the other side of the shoulder of the operator.

In the present state of the art the cord 43 for opening the matching hooks 17 and 18 is generally attached to an extra lever extending from approximately the screw 48 which pivotally connects the hooks 17 and 18. In the present invention the operating cord 43 is secured to the thumb piece or arcuate extension 19 of the hook 18 thereby 60 eliminating the extra lever and providing a greater leverage for the operation of the said hook; therefore a greater tension may be applied to the spring 18 and consequently a greater purchase may be obtained upon 65 various articles and tools.

In operation the hooks 17 and 18 are partially rotated when the arm of the operator is bent to carry the artificial hand toward the head, as when placing a hat, combing the hair, eating, or brushing the teeth, by means 70 of the cord 32 which cord is brought into tension when the said arm is bent.

The tension of the cord 32 will move the latch 22 to partially rotate the sleeves 7 and 11 and thereby partially rotate the hooks 17 75 and 18. The arrangement of this latch 22 also provides a means whereby a greater leverage may be obtained over the device generally used in the present state of the art.

As the latch 22 is removed by the cord 32 80 it in turn rotates the flange 8 and sleeve 7 as well as the sleeve 11 and radially grooved flange 12 thereon which flange 12 by engaging the pin 14 also rotates the shank or stud of the hook 17 and matching hook 18 85 pivotally connected thereto.

When the hands is returned to a normal or straight position as indicated in Fig. 1 of the drawings the flange 8 and the hooks 17 and 18 operatively connected thereto are 90 instantly returned to a normal position by means of a spring 5 having one end attached to the periphery of the annular flange 8 of the sleeve 7 and after traversing a portion of the periphery of said flange 8 has the 95 other end thereof secured to the metallic cup 2 as at 10.

The hooks 17 and 18 may be readily and easily detached by moving the latch 22 inwardly against the tension of the spring 27 100 whereby the aperture 23 will be moved into registration with the bevel headed screw 24 and thereby disengage said screw and the hooks 17 and 18 may be easily removed. In placing the hooks 17 and 18 of the shank 105 16 within the sleeve 11 and moving it inwardly with sufficient pressure to cause the bevel head 24 of the screw 26 to move the latch 22 longitudinally until said screw head passes through the aperture 23 when 110 the tension of the spring 27 will return the latch to engage the screw.

I am aware that the present state of the art discloses artificial hands comprising matching hooks rotated at the wrist when 115 the arm is bent, I therefore do not wish to claim such a combination broadly but—

What I claim as new and desire to secure by Letters Patent is—

1. An artificial hand comprising a socket; 120 a peripherally slotted cup mounted on the socket and provided with a hollow extension; a hollow member rotatably mounted in the extension; a shank rotatably mounted in the member and adapted to be ad- 125 justed therein to different radial positions; said shank having hooks at its outer ends; means for retaining the shank in its ad- 130 justed position in the member; and means extending through the slot in the cup for 135

detachably retaining the shank in a fixed position longitudinally within the member, the last-mentioned retaining means having operative means connected therewith outside of the cup for rotating the member and therewith also the shank and the hooks.

2. An artificial hand comprising a socket; a peripherally slotted cup mounted on the socket and provided with a hollow extension; a hollow member rotatably mounted in the extension and having a groove in one end; a latch slidably mounted in the groove and extending through the slot; a shank mounted in the member and retained therein by the latch, said shank having hooks at its outer end; and means connected with the latch outside of the cup for rotating the member and therewith also the shank and the hooks.

20 3. An artificial hand comprising a socket; a peripherally slotted cup mounted on the socket and provided with a hollow extension; a hollow member rotatably mounted in the extension and having a transverse groove in one end and radial grooves in its other end; a latch slidably and yieldingly mounted in the transverse groove and extending through the slot; a shank rotatably

mounted in the member and detachably retained therein by the latch, said shank having hooks at its outer end; means connected with the latch outside of the cup for rotating the member and therewith also the shank and the hooks; and means upon the shank adapted to engage a selected radial 35 groove for holding the shank in a fixed position radially within the member and adjustment to any other similarly fixed position being possible by the yielding engagement of the latch with the shank.

40 4. An artificial hand comprising a socket; a cup mounted on the socket and provided with a hollow extension; a shank mounted within the hollow extension and adapted to slide longitudinally therein, said shank 45 having hooks at its outer end and a projection at its inner end; and means for yieldingly engaging the projection in order to retain the shank within the hollow extension, the projection being adapted to force 50 retaining engagement with the retaining means when the projection is pressed against the retaining means.

In witness whereof, I hereunto set my signature.

DAVID HIRSCH.
